PIPE JOINT FOR WATER HEATERS

Fritz Koetting, Brooklyn, N. Y.

Application January 24, 1948, Serial No. 4,099

6 Claims. (Cl. 285—5)

1

This invention relates to new and useful improvements in heat exchangers such as a water heater for use with a suitable source of live steam.

More specifically, the present invention proposes the construction of such a water heater or heat exchanger including a shell having a plurality of longitudinal tubes, and bends interconnecting the tubes, the bends and tubes being connected so that any tube may be conveniently removed from the shell for cleaning and repair.

Another object is to provide a boiler as aforesaid which can be readily adapted for either parallel or series flow through the steam tubes, and which may employ one or more steam inlets and one or more steam outlets. The invention contemplates the provision of fittings used in interconnecting the tubes and the bends which are constructed and located for convenience in removing any tube from the boiler shell.

Accordingly, another object of the invention is to provide a boiler as aforesaid equipped with improved fittings for connecting the tubes to the shell.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a side view of a water heater constructed in accordance with this invention.

Fig. 2 is a view of the left end of the boiler.

Fig. 3 is a section on the line 3—3 of Fig. 1.

Fig. 4 is a view similar to Fig. 2 showing the tubes connected in series.

Fig. 5 is a sectional view showing the connections between tubes, shell and bends.

Figs. 6, 7 and 8 are views similar to Fig. 5 showing other embodiments of the invention.

The water heater, according to the form of the present invention shown in Figs. 1-5, includes; a shell 10, for containing water to be heated, and having end walls 11 and 12. The shell has a water inlet 13 and a water outlet 14. Each end wall is provided with a plurality of threaded orifices 15, see Fig. 5. There is a bank of straight tubes 16 in the shell.

Referring to Fig. 2, it will be seen that, as one exemplification of the present invention, the tubes 16 are arranged to two sets on opposite sides of a longitudinal center plane of the shell, the shell being circular in cross section. The two uppermost tubes are horizontally aligned and have no

2

U-bends, being open for connection with the steam exhaust. They form the outlets 34 for the bank of tubes. These two outlets 34 may be connected by a forked pipe if desired so that they will both exhaust into a single pipe.

In a similar manner the bottom two pipes form the steam inlets 35. These inlets may be supplied from any suitable source of live steam. The inlets are shown at one end of the shell and the outlets at the other, but they may be at the same end if desired. Adjacent tubes are then connected in series by U-bends 30. Thus the two sets of tubes of the bank are in parallel and the tubes of each set are in series. The tubes are so spaced that they may be connected by similar bends 30. Also the inlets and outlets are similarly spaced so that they may be connected by bends 30 if desired. For example, the outlets 34 might be connected by a bend 30. Then the ends 34 of the top tubes would serve one as an inlet and the other as an outlet and all the tubes of the shell would be in series, eliminating any parallel flow.

The tubes may also be arranged so that their centers are disposed at the apices of a pattern of equal equilateral triangles or equal squares for example, so that each tube will be equidistant from at least two other. Such an arrangement will permit the bends 30 to be readily changed to interconnect the tubes in a new flow arrangement without changing the span of any bend. One or more tubes may thus be cut out of service, and by suitably plugging the openings in the end walls from which any such tube is removed, the boiler or heat exchanger may be restored to service while the old tube is being repaired or a replacement tube procured. More tubes than those shown may be employed if desired.

The series arrangement described may also be obtained as shown in Fig. 4. A lesser number of tubes is shown than in Figs. 1-3, and these are connected in series. The steam inlet 35 is shown at the bottom of the boiler so that steam with the greatest heat content is effective at the bottom of shell 10 where the coldest water will tend to accumulate. The increased temperature difference increases the efficiency of heat transfer through the walls of the tubes and further causes greater circulation of water within the boiler shell by producing more convection currents.

The tubes may be assembled as shown in Fig. 5. A flanged fitting 51 is screwed into end wall 12 by means of the usual tapered pipe threads. Tube 16 is similarly threaded into flange 53 and fits freely in fitting 51. Bend 30 is also similarly threaded into flange 54. Gaskets 55 are inserted

between adjacent flanges as indicated. Bolts 56 pass through clearance holes in flanges 53 and 54 and gaskets 55 to engage threads tapped in flange 51.

In assembling a tube 16 in the boiler, flanged fittings 51 are first inserted in both end plates 11 and 12 and are tightened in the usual manner. A tube 16 is then slid through flanges at opposite ends of the boiler and a gasket 55 is placed over each projecting end. A flange member 53 is then screwed over the threaded portion of each end, and tightened. The length of the tube 16 and the cutting of the end threads thereon is such that this tightening may be accomplished without interference from the gasket 55 and so that the bolt holes may be brought into alignment. Flange 54 which is threadedly secured to bend 30 is then placed in position with an additional gasket 55. Bolts 56 are then threaded into tapped holes in fitting 51. As bolts 56 are tightened, flanges 53 and 54 and gaskets 55 are compressed against the face of fitting 51, providing a joint which is tight against both steam and water.

The tightening of bolts 56 also compresses tube 16 so that it will bow slightly in the middle, and will thus be able to adjust itself to dimensional changes which accompany non-uniform temperature changes in the boiler or heat exchanger.

If the bowing of tube 16 is not desired, a modified form of the invention, as shown in Fig. 6, may be used. In this form, a gland or stuffing box 61 is threaded into end wall 12 of boiler 10. Any desired form of gland or stuffing box may be used and it has been shown as comprising an outer portion 62 shaped to receive packing 63 which is compressed by nut 64 against the exterior surface of tube 16 to form a water tight joint through which tube 16 may slide. This sliding connection permits the dimensional changes above described to occur without bending of the tube 16.

Bend 30 is secured to the end of tube 16 by the usual union 61 which is shown as comprising two flanged members 65 and 66 which are held together by an internally threaded annular clamping member 67, leakage being prevented by gaskets 68 and 69. The ends of tube 16 and bend 30 are threaded into the union in the usual manner.

Referring to the construction shown in Fig. 7, a plate or disc 17 is secured to the outer face of each end wall 11 and 12 and this disc 17 has a threaded orifice 18 in line with the orifice 15. An externally threaded fitting 19 is screwed into the aligned orifices 15 and 18 and extends slightly into the interior of the shell 10. The fitting 19 has a circular flange 20 superposed on the disc 17 with packing therebetween.

The fitting 19 is provided with internally threaded recesses 22, and a fitting 23 having a flange 24 similar to the flange 20 is connected thereto; flange 24 being superposed on the flange 20 with the packing 25 therebetween and flange 24 having orifices in line with the recesses 22. Bolts 27 are passed through the orifices 26 and into the recesses 22 for connecting the two flanges together.

A pipe 28 is welded to the flange 24 and forms another part of the fitting and extends outwardly therefrom and is externally threaded and connected to one leg 29 of a U-bend 30 by a union 31, the connection being sealed by a packing 32.

The fitting 19 is internally threaded at 33, at

its ends opening into the shell. The tube 16 is externally threaded at each of its ends and screwed into the aligned threads 33 of two opposed fittings 19 disposed in the opposite walls 11 and 12.

In assembling the tubes in the shell so that they may be removed for cleaning, inspection or repair, a fitting 19 is first secured to one end of each tube and a fitting 19 is screwed into the orifices 15 of one wall only. That is, fittings 19 may be screwed into the holes of the wall 11 but not into wall 12. The tubes are then slid through the orifices 15 of the wall 12 until their fittings 19 reach the orifices 15, whereupon their fittings 19 are screwed into the orifices 15 of wall 12 and at the same time the other ends of the tubes are screwed into the threads 33 of the other fittings 19 in the wall 11.

After the tubes are in place and the flanges 20 turned tightly against the packing 21, the fittings 23 can be attached first and then the bends 30 can also be attached. The tubes may be removed by a reversal of this procedure.

In the embodiment of the invention shown in Fig. 8, the same advantages are present as in the embodiments of Figs. 5, 6 and 7, but are attained by a somewhat different construction. Instead of the fittings 19, straight externally threaded pipes 19' are screwed into the orifices 15' and 18' and extend beyond both ends thereof. The pipes 19' have threads 33' for the tubes 16'. A fitting 23' is screwed on each pipe 19', each fitting 23' having an internally threaded portion 24' which is screwed on the outer end of the pipe 19' to compress the packing 21' against the disc 17' and packing 25' against the pipe 19'. Each fitting also has a pipe portion 28' connected to a U-bend 30' by a union 31'.

From the foregoing, it will be seen that an assembly has been provided permitting the ready removal of tubes for repair or cleaning, and a fully steam tight packed joint has been provided nevertheless.

If the bowing of tubes 16 is desired, then the arrangements of Figs. 5, 7 and 8 may be used. If the bowing action is considered to be undesirable by reason of the short length of the boiler or the large diameter of the tubes, for example, then the embodiment of Fig. 6 may be used.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A heat exchanger of the class described comprising a shell having end walls, aligned threaded orifices in said end walls, fittings screwed in said orifices and having internal threads, tubes in said shell screwed into said internal threads of aligned fittings so that they can be removed from said shell by unscrewing the fitting at one end thereof from said end wall adjacent thereto, all of said tubes being evenly spaced from adjacent tubes, and U-bends connecting adjacent tubes.

2. A heat exchanger of the class described comprising a shell having end walls, aligned threaded orifices in said end walls, fittings screwed in said orifices and having internal

threads, tubes in said shell screwed into said internal threads of aligned fittings so that they can be removed from said shell by unscrewing the fitting at one end thereof from said end wall adjacent thereto, all of said tubes being evenly spaced from adjacent tubes, and U-bends connecting adjacent tubes for forming of said tubes a single series flow bank having one inlet and one outlet.

3. A heat exchanger of the class described comprising a shell having end walls, aligned threaded orifices in said end walls, reinforcing discs over said orifices on the outer faces of said end walls, said discs having threaded orifices in line with said end wall threaded orifices, a fitting including a neck screwed into each aligned disc and end wall orifices and a flange superposed on said disc, said flange having internally threaded recesses and said neck having internal threads, tubes screwed into opposed neck threads, a fitting having a flange superposed on said first mentioned flange, bolts securing said flanges together and screwed into said recesses, and a U-bend leg connected to each of said last mentioned fittings.

4. A connection for securing a tube in a shell end wall for permitting removal of said tube from said shell, said shell end wall having a threaded orifice comprising a flanged pipe adapted to be screwed into said end wall orifice and having internal threads adapted to receive a threaded end of said tube, the outer face of said flange having threaded recesses, a flanged fitting superposed on said flange and secured thereto by bolts screwed into said recesses, said fitting having an externally threaded neck, and a U-bend leg secured to said neck threads by a threaded union.

5. A heat exchanger of the class described

comprising a shell having opposed end walls provided with aligned threaded orifices, flanged pipes screwed into said orifices with their flanges engaging the outer faces of said end walls, said flanged pipes having internal threads, externally threaded tubes screwed into aligned pipes whereby when a fitting is unscrewed from its end wall orifice it will carry its tube with it and unscrew its said tube from the opposed fitting for removal of the tube from the shell.

10 6. A heat exchanger of the class described comprising a shell having opposed end walls provided with aligned threaded orifices, flanged pipes screwed into said orifices with their flanges 15 engaging the outer faces of said end walls, said flanged pipes having internal threads, externally threaded tubes screwed into aligned pipes whereby when a fitting is unscrewed from its end wall orifice it will carry its tube with it and unscrew its said tube from the opposed fitting for 20 removal of the tube from the shell, a U-bend, and means for connecting said U-bend to said flanged pipe.
